CLAIM

The ornamental design for a cheval-glass, as shown and described.

DESCRIPTION

FIG. 1 is a front perspective view of a cheval-glass in accordance with the design of the present invention. FIG. 2 is a front perspective view of the embodiment illustrated in FIG. 1 with the mirror member rotated by 180 degrees.

FIG. 3 is a top perspective view of the mirror member with the base member being omitted for ease of illustration.

FIG. 4 is a bottom perspective view of the mirror member illustrated in FIG. 3.

FIG. 5 is a top perspective view of the base member, with the mirror member being omitted for ease of illustration.
